CIGARETTE HOLDER

Sergio De Pinto, Staten Island, N. Y., assignor of one-tenth to Salvatore Mezzacappa and Lucy Mezzacappa, both of Staten Island, and one-tenth to William Auerbach, New York, N. Y.

Application May 3, 1950, Serial No. 159,758

5 Claims. (Cl. 131—175)

1

This invention relates to smoking utensils and more specifically to a cigarette holder.

One of the objects of the invention is a cigarette holder with ash disposal means which excludes fire hazards and permits smoking in crowded rooms where smoking is usually otherwise not permitted.

A more specific object of this invention is a cigarette holder having an ash container attached thereto and providing for automatic feed of the cigarette end into the ash container.

Fig. 1 shows perspectively a cigarette holder with an ash container.

Fig. 2 shows a cigarette holder according to Fig. 1 in section and in one of its operative positions.

Fig. 3 represents another operative position of the cigarette holder.

Figs. 4 and 5 represent in front and side elevations respectively, an ash container used for the purpose of this invention.

Fig. 6 represents a certain sub-assembly of elements shown in Fig. 2.

Fig. 7 represents another sub-assembly of such elements.

Figs. 8 and 9 represent side and end views respectively of a member supporting the ash container.

Figs. 10 and 11 represent end and side views of a sleeve forming part of the ash container.

Figs. 12 through 15 represent views of a stopping member as a part of the ash removing mechanism; Fig. 12 represents a side view of the stopping member; Fig. 13 is a view on Fig. 12 from the right and Fig. 14 a view on Fig. 12 from the left. Fig. 15 represents a perspective view of the stopping member.

In Fig. 1 part 1 represents diagrammatically a tube for receiving a cigarette and part 2 a mouthpiece attached to tube 1 to permit smoking of such cigarette. Tube 1 is supported in a bushing 3 which in turn forms an insert in bowl 4. Bowl 4 serves as an ash container. It has a cover 5 having ventilation openings 43 and held by metal clamps 6 so that it may be easily removed and put back if desired to permit ash removal. Diametrically arranged with respect to bushing 3, there is another and similar bushing 7 supporting an adjustment member 8 which will be described further below.

Bushings 3 and 7 are shown in Figs. 8 and 9 in side and end elevations respectively. They are provided with outside threads 39 fitting into corresponding openings of bowl 4 and with inner threads 40 for receiving tubular member 1 and metal sleeve 31, as described below, respectively.

2

Bushings 3 and 7 are also provided with circumferential openings 41 also shown schematically in Fig. 9, to permit access of air to the inside of bowl 4 and also to prevent excessive heat from reaching tubular member 1 and sleeve 31.

The elements just enumerated may be made of any appropriate material, for example, mouthpiece 2 of hard rubber; tube 1 of metal such as aluminum; bushings 3 and 7 also of metal such as brass; bowl 4 of wood or plastic; cover 5 of wood, plastic or metal; clamp 6 of metal; and adjustment member 8 also of metal, such as brass, or of plastic such as "Bakelite."

Mouthpiece 2 is provided with an inner thread 16 to be screwed over an insert 11 made of metal such as aluminum. Insert 11 is also provided at 12, with another thread screwed into metal tube 1 supporting the cigarette in a manner described further below.

Insert 11 also serves to receive a filter of anti-nicotine material such as shown schematically at 14. Insert 11 also supports around portion 15, a tension spring 16, as also shown more clearly in the sub-assemblies of Figs. 6 and 7.

Spring 16 normally presses metal sleeve 18 against the inner end of cigarette 17 supported in sleeve 18.

Sleeve 18 is important for the purpose of the invention. It serves to assure straight feeding of cigarette 17 to the point of its use or burning.

Sleeve 18 has a tubular section 19 for receiving the inner end of cigarette 17 to assure the proper axial position of cigarette 17. At its bottom, tubular portion 19 narrows down to an annular projection 20 which forms the seat for the inner end of cigarette 17 and prevents cigarette 17 from being pushed into sleeve 18 further than necessary for the proper seating and alignment of cigarette 17 with respect to tubular portion 19.

Another tubular portion 21 of sleeve 18 serves to guide sleeve 18 and thereby cigarette 17 in its axial movement inside tube 1.

Tubular portion 21 is also circumferentially engaged by spring 16 and thus normally pushed in the direction of arrow 22.

Spring 16 is so dimensioned that it assures continuous pressure against sleeve 18 and cigarette 17 into direction 22 until the cigarette is practically consumed and the inner end of cigarette 17 has reached the outer end of tube 1. In this case, tubular portion 19 of sleeve 18 will pass into the inner diameter of a thin ring or projection 23 provided at the end of tube 1 inside thereof.

Sleeve 18, however, under the pressure of spring 16, will not be able to pass through ring 23 completely, because it will be prevented from passing through ring 23 by the larger diameter of tubular portion 21 sliding inside tube 1.

In this way, it will be assured that cigarette 17 may be smoked to the fullest extent possible without, however, risking that the driving or supporting mechanism for the cigarette is pushed into the open and out of control.

Bowl 4 is preferably made out of briar to insure heat resistance as well as heat insulation to the best possible degree.

However, any other appropriate natural or synthetic material may be used for this and any other elements described herein without exceeding the scope of this invention.

Cigarette 17 on its way from the inside to the outside of tube 1 under control of spring 16 is pushed with its outer end against stop member 26 preferably made of metal wire such as shown in Figs. 12 to 15 inclusive.

Stop member 26 is shown to consist of a ring portion 27 which has just the diameter of cigarette 17 thus preventing the cigarette 17 from slipping through ring 27; yet at the same time ring 27 will permit the ash to pass inside ring 27 as indicated in Fig. 2 by dotted line 36 and to extend through the conical space formed by the four legs 28. Legs 28 as shown more clearly in Fig. 15 form the four sides of a four sided pyramid attached at its base to ring 27, and the legs 28 converge at the top to a common junction point 29. From this common junction point 29, there extend four further legs 30 which form a spider type clamping device fitting over adjustment member 8.

In Fig. 3 adjustment member 8 is shown to consist of an operating or handling flange or knob 31 extending from a tubular sleeve 32 over the free end of which the legs 30 of stop member 26 are fitted or clamped.

Stop member 26, under the control of a tension spring 33, is urged normally against the outer or burning end of cigarette 17.

Spring 33 is substantially stronger than spring 16 thus preventing stop member 26 from being pushed outwardly by spring 16. Spring 33 as shown in Fig. 3, if moved inwardly, merely serves to urge continuously sleeve 32 and stop member 26 clamped thereon into contact with the end of cigarette 17, thus holding that cigarette end 36 substantially in the center of ash container 4 and forcing the ash of the cigarette to feed into the cone formed by legs 28 as shown in Fig. 2.

Sleeve 32 and flange or knob 31 of adjustment member 8 are hollow; an opening 34 extends from the atmosphere through stop member 26 to the cigarette end, thus permitting the cigarette to be lighted.

Another purpose of adjustment member 8 is to permit extinction of the cigarette. By pulling knob 31 into the direction of arrow 35 (Fig. 3), the burning cigarette end, shown in Fig. 3 at 36 will be pushed by spring 16 into a substantially peripheral position with respect to ash container 4, and enter sleeve 31. Sleeve 31 is supported, as already stated above, by screwing into bushing 7, which in turn is screwed into bowl 4 at a point diametrical with respect to bushing 3 shown in Fig. 1. For this purpose sleeve 31 as shown in Figs. 10 and 11 is also provided with an outer thread 42 to permit its attachment inside of bushing 7 by means of thread 40.

The cigarette holder operates in the following manner:

Cigarette 17 supported in tubular portion 19 will be in smoking position as long as its end 36 is pushed against stop member 26 under control of spring 16 and as long as stop member 26 is positioned in the center of ash container 4 thereby maintaining the cigarette end 36 in that position.

10 In order to extinguish cigarette end 36, adjustment member 8 is moved in the direction of arrow 35 (Fig. 3). This will permit the cigarette end 36 still under control of spring 16 to enter sleeve 31 and assume substantially a peripheral position with respect to ash container 4. In this position and by contact with the relatively large heat conducting surface of metal sleeve 31 and at the same time due to reduced access of air (which in this position can enter from one side only through opening 34, while in the central position of the cigarette end 36, the air is accessible from all sides) the cigarette will be extinguished.

In order to relighten or lighten the cigarette end 36 it is only necessary to release adjustment member 8 so that stop member 26 under control of spring 33 will move in a direction opposite to arrow 35 so that cigarette end 36 will again assume a position defined by stop member 26 in the center of ash container 4. Lighting of the cigarette is then effected by placing a flame at opening 34 and sucking at mouthpiece 2 in otherwise well known manner.

Thus while extinguishing and lighting can be effected in extremely simple manner, smoking itself is made extremely efficient.

The invention is not limited to the use of all the elements in the form shown and described but the structure may be varied without departing from the scope of this invention.

I claim:

1. A cigarette holder, comprising an ash container, means to permit a cigarette to enter said container, including a tubular member extending into said container at one end thereof for receiving the cigarette and a spring member arranged within said tubular member for pushing one cigarette end into said ash container, a metal sleeve in said container, and a stop member slidably supported in said metal sleeve and extending into said ash container at the end thereof which is opposite to the cigarette receiving end for stopping said cigarette end in two predetermined positions with respect to said container, namely, a position in which the cigarette end is substantially in the center of the container, and a substantially peripheral position with respect to the ash container in which the cigarette end is surrounded by said metal sleeve.

2. A cigarette holder comprising an ash container, means to permit air to enter said container, including a tubular member extending into said ash container at one end thereof for receiving the cigarette, and a spring member arranged within said tubular member for pushing one cigarette end into said ash container; an adjustable stop member extending into said ash container at the opposite end thereof for stopping said cigarette end, a metal sleeve in said ash container for slidably supporting said stop member, and a spiral spring of cylindrical shape closely following the inside of said sleeve and arranged to oppose the sliding movement of said stop member in one direction, said stop member being formed at one end so as to engage said cigarette end substantially along its periphery.

only and being adjustable in two predetermined positions, namely, a substantially central position in which said cigarette end is exposed to air permitting it to burn, and a substantially peripheral position with respect to the ash container in which said cigarette end is surrounded by the metal sleeve causing it to be extinguished.

3. A holder according to claim 1 wherein said stop member includes a hollow end portion, having lateral openings and circumferentially engaging the cigarette end and wherein said metal sleeve includes a relatively large heat conducting surface surrounding said cigarette end while in said peripheral position.

4. A holder according to claim 1 comprising a metal bushing in said ash container supporting said tubular member and having circumferential openings to permit air circulation.

5. A holder according to claim 2 comprising a metal bushing supporting said metal sleeve and having circumferential openings to permit air circulation.

SERGIO DE PINTO.
